UNITED STATES PATENT OFFICE.

CHARLES W. BROWN AND EDWIN H. BROWN, OF WASHINGTON, D. C.

FURNITURE FOR PRINTERS' FORMS.

SPECIFICATION forming part of Letters Patent No. 340,548, dated April 27, 1886.

Application filed October 26, 1885. Serial No. 180,989. (No model.)

To all whom it may concern:

Be it known that we, CHARLES W. BROWN and EDWIN H. BROWN, residing at Washington, in the District of Columbia, have invented 5 certain new and useful Improvements in Furniture for Printers' Forms, of which the following is a specification, reference being had therein to the accompanying drawings.

This invention relates to furniture for printers' use.

The invention consists in a variety of furniture having a metallic core and side pieces and a filling of wood, papier-maché, or similar material lighter than metal, whereby the furniture is made lighter and cheaper than if made entirely of metal, and is more uniform and durable than if made of wood alone.

In the drawings, Figure 1 is a perspective view of a piece of furniture having metallic core or cross-bar and metallic side strips. Fig. 2 is a cross-section of the same on the line *x x*.

20 A A indicate the side plates of the furniture, which rest against the type in the form or against the chase.

25 B is a cross-bar or binding-strip, which connects the two side plates, A A, but serves as a spreader to hold them apart.

The space between the plates A A alongside 30 the spreader is filled with a strip of wood, papier-maché, or similar material, C, which material serves to keep the plates A A parallel with each other, and holds them to offer resistance to side-pressure.

35 As shown in Figs. 1 and 2, the plates have

preferably a slight overhang, so that the filling-piece C is held as in a dovetail groove.

The pieces C are preferably slightly concave at the outer surface, so that if any water is absorbed by the wood or material of which this 40 filling-piece is composed the expansion serves rather to fill the concavity than to expand the side plates, A, out of parallelism.

When wood is used as the material of the filling-pieces, the wood is preferably chemically treated, so that it will absorb water with 45 difficulty or not at all.

The metal part is preferably cast integral about the filling-pieces, but in some cases the metal may be prepared first and the filling- 50 pieces afterward applied.

We claim—

1. A piece of printers' furniture having metallic side plates connected by a longitudinal binding-strip or spreader, as described, 55 and strips of wood covering both faces of the spreader, substantially as described.

2. The combination, with the metallic side plates and spreader-bar, the side plates having overhang, as described, of the beveled strips 60 secured against the spreader in the dovetail groove, substantially as described.

In testimony whereof we affix our signatures in presence of two witnesses.

CHARLES W. BROWN.
EDWIN H. BROWN.
